(57) **CLAIM**

The ornamental design for a refrigerator interior with color, as shown and described.

DESCRIPTION

FIG. 1 is a front perspective view of a refrigerator interior with color according to a first embodiment of our design in a closed configuration, a second embodiment being a mirror image thereof;

FIG. 2 is a front elevational view thereof;

FIG. 3 is a back elevational view thereof;

FIG. 4 is a left side view thereof;

FIG. 5 is a right side view thereof;

FIG. 6 is a top view thereof;

FIG. 7 is a bottom view thereof;

FIG. 8 is a front perspective view of a refrigerator interior with color according to the first embodiment of our design in an open configuration, the second embodiment in the open configuration being a mirror image thereof;

FIG. 9 is a front elevational view thereof;

FIG. 10 is a back elevational view thereof;

FIG. 11 is a left side view thereof;

FIG. 12 is a right side view thereof;

FIG. 13 is a top view thereof;

FIG. 14 is a bottom view thereof;

FIG. 15 is a top-front perspective, cross-section reference view of the refrigerator interior with color according to the third embodiment of our design in the open configuration taken along line 15, 16 in FIG. 13; and,

FIG. 16 is a front perspective view thereof.

The broken line showing of various features is for the purpose of illustrating unclaimed portions of the refrigerator interior with color and forms no part of the claimed design. Dash-dot lines adjacent un-shaded areas represent bounds of the claimed design and form no part of the claimed design themselves.

The stipple fill is used to indicate a charcoal gray color having the following color characteristics according to the CIELAB system:

L: 25 to 45

a: 0 to -2

b: 0 to -2.
